Primary Examiner — Selina Sikder(74) *Attorney, Agent, or Firm* — Mark E. Rose; Philip N. Smith(57) **CLAIM**

The ornamental design for buttons for a remote control, as shown and described.

DESCRIPTION

FIG. 1 is a perspective view of buttons for a remote control according to our new design.

FIG. 2 is a front view thereof.

FIG. 3 is a left side view thereof.

FIG. 4 is a right side view thereof.

FIG. 5 is a top view thereof; and,

FIG. 6 is a bottom view thereof.

The rear view forms no part of the design and is omitted. The broken lines showing portions of the drawings are for the purpose of illustrating environmental structure and form no part of the claimed design.

1 Claim, 4 Drawing Sheets See application file for complete search history.
